UNITED STATES PATENT OFFICE.

RALPH L. MORGAN, OF WORCESTER, MASSACHUSETTS, ASSIGNOR TO GREENFIELD TAP AND DIE CORPORATION, OF GREENFIELD, MASSACHUSETTS, A CORPORATION OF MASSACHUSETTS.

GRINDING MACHINE.

Original application filed November 20, 1920, Serial No. 425,475. Divided and this application filed March 12, 1923. Serial No. 624,358.

This application is a division of my prior application Serial No. 425,475, filed Nov. 20, 1920 and relates to a grinding machine operated by fluid pressure, applied and controlled by certain novel constructions, arrangements and combinations of parts which are hereinafter described and more specifically pointed out in the appended claims.

10 It is the object of my present invention to provide a grinding machine having an improved fluid operated driving mechanism, together with improved controlling devices therefor by which relative feed of the work 15 and the grinding wheel may be conveniently secured and by which the flexibility of control of the feed may be greatly increased.

A further object of my invention is to provide in a grinding machine certain improved mechanism and controlling devices 20 therefor by which a relatively rapid feed may be quickly and easily obtained when desired, such rapid feed being designed for use during relative movement of the parts 25 toward and from operative relation.

In the present embodiment of my invention, I have shown my improvements adapted to reciprocate the work table of an internal grinding machine. Auxiliary mechanism is also shown by which the cross feed 30 of the grinding wheel may also be actuated and controlled.

A grinding machine embodying my invention is shown in the accompanying drawings, in which—

Fig. 1 is a front elevation of the machine; Fig. 2 is an end elevation;

Fig. 2^a is a detail of the grinding wheel belt tightener;

40 Fig. 3 is a sectional elevation on an enlarged scale of Fig. 1;

Fig. 4 is a cross-section on line 4—4 of Fig. 3;

45 Fig. 5 is a side elevation on an enlarged scale of the throttle valve and operating handle;

Fig. 5^a is a detail front elevation of the lower end of the operating handle;

50 Fig. 6 is a sectional elevation on an enlarged scale of the main valve;

Fig. 7 is a cross-section on the line 7—7 of Fig. 6;

Fig. 8 is a cross-section on the line 8—8 of Fig. 6 on a still further enlarged scale;

Fig. 9 is a front elevation of the parts 55 shown in Fig. 8;

Fig. 10 is a front elevation partly in section of the automatic cross feeding mechanism for the grinding wheel;

Fig. 11 is a cross-section on the line 11—11 60 of Fig. 10 on an enlarged scale; and

Figs. 12, 13 and 14 are diagrams illustrating the operation of the valve mechanisms which control the operation of the work table.

The invention will be best understood by a detailed description of the parts and connections.

Referring to the drawings and in detail, A designates the frame or base. This base has a lengthwise extending V and a flat way and a work table B is fitted to slide back and forth thereon. Bolted to this work table is a bearing block C, in which is journalled a shaft D on the end of which is screwed the chuck E which holds the piece of work or blank which is to be ground. A pulley F is secured on the shaft D and the block is made hollow so that the shaft can be driven from below and the pulley covered up so as to be out of the way of the operator.

A driving shaft 10 is journalled in bearings or brackets secured to the rear of the base A and the same is driven by a pulley 11 secured on the same to which a belt may be led from a suitable countershaft. A pulley 12 is also secured on the shaft 10 and is employed to drive the oil pump hereinafter referred to. A cradle G is carried by the shaft 10 and extends inside of the base A. This cradle consists of two arms 13 pivoted on the shaft 10, said arms being connected together by a tying member 14.

A drum 15 is mounted on a shaft 16 which is journalled in bearings 17—17 formed or carried on the arms 13—13 as illustrated in Fig. 4. A belt 18 is led around said drum 15 and around the pulley F. The pulley F is flanged as shown in Fig. 3 so that as the work table is reciprocated back and forth on the base, the chuck E will be rotated, the belt moving along the drum 15. The weight of the cradle and the parts

which are carried thereby is relied upon to keep the belt 18 under tension. A wire rope 19 is connected to the cradle and is led up over a small pulley or wheel secured inside 5 of the frame and the end of the rope is attached to a lever 20 pivoted to the back of the frame and extending out through an inverted L-shaped slot in the front of the frame. A foot piece or treadle 22 is attached to the front end of the lever. By pressing down on the treadle and moving the same to the left as shown in Fig. 1, the front end of the cradle will be raised and locked in raised position so that tension 10 will be taken off of the belt 18 whereby the rotation of the work holding chuck E will be stopped.

An arch shaped support H is secured to the base A as illustrated in Fig. 2. This 20 support is made in this shape so that the work table B can pass under the same. This support H is provided with a transversely extending dove-tail, fitted to slide on which is a bearing block I secured in which is a bearing quill, journaled in which, preferably by ball bearings, is a shaft J which carries a grinding wheel K on one end and a driving pulley L on the other end. An arm 23 is pivoted to a slide 230, fitted on ways 25 formed on a bearing block I as illustrated in Fig. 2. This slide is normally forced to the rear by a spring 231 housed in the same and fitted on a threaded shaft 232, one end of which is threaded into the bearing block. 30 A nut 233 is screwed on the shaft 232 to limit the rearward movement of the slide 230 in case the grinding wheel driving belt should break. A shaft 24 is journaled in the arm 23 and carries on one end a pulley 40 25 which is driven by a belt 26 extending from a suitable countershaft. Secured on the other end of the shaft 24 is a pulley 250, and the grinding wheel driving belt 251 is led around the same and around idler 45 pulley 234 journaled on a stud secured in the slide 230, and around driving pulley L. A weight 28 is hung on the pivoted arm 23. By these connections the grinding wheel K will be rotated at high speed and 50 the same can be moved transversely of the machine without effecting this rotation.

A cylinder M is secured inside of the base A near the top thereof. Fitting in the same is a piston N, secured to which is a piston rod N' which extends out through a stuffing box attached at the left of the cylinder M as shown in Fig. 3. The piston rod N' is connected at its left hand end to a block O secured to the left end of the work table B. This connection is preferably made yielding by placing collars 29-29 on the piston rod which is reduced or turned down at its left hand end. Nuts 30-30 are threaded in the end of the piston rod and

65 springs 31-31 are placed between said collars and the block O. By these connections as the piston N is forced to the right or left in the cylinder (Fig. 3) the work table will be correspondingly moved back and forth in the ways. A valve casing P is 70 secured to the front of the frame or base A and working in this valve casing is a main valve and two auxiliary valves, these valves being employed to control the flow of liquid to and from the ends of the cylinder M and thereby to control the movements 75 or reciprocation of the work table.

The liquid preferably a light oil which is employed to move the piston and thus to reciprocate the work table, is kept in a tank 80 S and is taken therefrom by a gear pump T and forced through a pipe 32 to a casing U which contains a throttle valve V operated by an operating handle W. The liquid passes from the valve casing U to the main 85 valve through a pipe 33.

The throttle valve construction is illustrated in detail in Fig. 5. The throttle valve V is preferably made conical in shape and is arranged to co-operate with a tapered 90 valve seat formed in a partition in the casing U. The valve V is formed or mounted on a stem 34 which is carried out through a stuffing box 35. A block 36 having trunnions or studs 37 is secured on the valve stem 34 by a taper pin and a spring 38 is arranged between said block 36 and the stuffing box 35 so as normally to force the throttle valve V to its seat to close the 95 same. The end of the valve stem 34 is fitted in a hole in an adjusting knob 39 threaded into a bracket extending outwardly forming part of the throttle valve casing U, a check nut 40 being threaded on the adjusting nut. The lower end of the operating 100 handle W is made in the form of a yoke and each prong thereof is slotted so as to engage the studs 37. Normally the valve stem 34 is forced outwardly to the bottom 105 or end of the hole in the adjusting nut 39. By turning the adjusting nut and by unlocking and locking the check nut 40, the amount 110 of normal opening of the throttle valve can be adjusted so that the speed of the normal movement or reciprocation of the work table 115 B can be determined. The normal position of these parts is illustrated in Fig. 4. By pulling the top of the operating handle outwardly from the front of the machine as illustrated by the arrow in Fig. 5, the 120 throttle valve can be opened as wide as desired and by this manual manipulation the speed of the work table can be increased to any desired degree within the limits of the design of the machine. This brings in an 125 important point of control as will be referred to more particularly after the valves have been described.

The main valve consists of three pistons 41, 42 and 43 arranged on a rod 44. A head or cylindrical projection 45 is screwed into the right hand end of the main valve casing 5 and a stuffing box 46 is arranged therein through which the rod 44 passes. The rod 44 is also fitted in a bearing 47 formed on the throttle valve casing U. A plug 48 is screwed into the other end of the main valve 10 casing.

Each auxiliary valve R consists of a piston 49 and a piston 50 formed on a stem 51 extending out through a stuffing box 52 screwed in the valve casing. The auxiliary 15 valves are oppositely arranged. The innermost pistons 50 are turned down or have beveled ends as shown so that if they butt together there will still be room for some oil to get between them as illustrated in 20 Fig. 13. The valve casing P is bored or formed with passages which are arranged as follows. The pipe 33 connects to a passage which is divided into two branches 53 and 54 controlled by pistons 41 and 43 of 25 the main valve. An exhaust passage 55 is controlled by the piston 42 of the main valve and this passage is connected by a pipe 56 to the oil tank S. A passage is connected by pipe 57 to the left hand end of the cylinder M and a passage is connected by pipe 58 to the right hand end of the cylinder M, the cylinder being provided at its ends with heads to which these pipes connect. The 30 pipe or passage 33 also connects by a passage 59 to the part of the casing in which the auxiliary valves operate. This passage has branches 60 and 61. The part of the valve casing which contains the auxiliary valves is connected to the left of the main 35 valve by a passage 62 and to the right of the main valve by a passage 63. This part of the casing is also connected to the exhaust pipe 56 by a passage 64 which is branched as at 65, the ends of the passages 64 and 65 also being branched out into two passages, 40 one to co-operate with the side and the other with the end of each piston 49 of the auxiliary valves. The ends of the main valve casing are connected by pipes 66 and 67 to 45 operate the traverse feed of the grinding wheel as hereinafter described.

The way the liquid flows through these various passages will be hereinafter detailed after the various other parts have been described.

The intermediate section of the operating handle W is formed into a rectangular loop or strap 68. A sleeve 69 is slidable on the cylindrical head 45 of the main valve, which 50 sleeve has an extending arm 70 which has at its end a block 71 through which the stem 44 of the main valve passes. The block 71 is fitted inside the strap 68 and these parts are secured together by a pivot bolt 72 (see 55 Fig. 5). The parts 69, 70 and 71 are pref-

erably made one integral piece and the arm 70 is shaped to clear the stuffing box 46 as shown in Fig. 6. An arm 73 is also preferably formed with the parts 69, 70 and 71 and a stud 74 is held therein by a suitable 70 nut (see Figs. 8 and 9). A rocker wing 75 is secured on the stem of the right hand auxiliary valve R and the same has a slot 76 into which the stud 74 fits.

By this arrangement, the operating handle 75 W can be moved to the right or left around the studs 37 as a pivot and this movement will push the main valve Q to the right or left. Also the top of the operating handle can be pulled outwardly or away from the frame of the machine, in this operation the stem or rod 44 of the main valve acting as a pivot. This operation will correspondingly open the throttle valve. This operation can take place no matter how the handle stands longitudinally of the machine. When the handle W is pulled outwardly the rocker wing 75 is partly rotated as indicated in dotted lines in Fig. 8 for a purpose hereinafter described.

The work table B is provided along its front face with a T slot 77. A dog 78 is fitted into this slot and is provided with a latch 79 hung on a screw 80 by which the dog is clamped in adjusted position. The 90 top of the latch 79 is shaped to engage a projection 81 on the dog 78 and the latch is kept to the right (Fig. 6) by a plunger 82 and a spring 83. The latch thus forms a pawl, the lower end of which can be moved to the left as shown in Fig. 3 against a spring tension. Another or left hand dog 84 is secured in the slot 77 by a locking bolt 85. An engaging screw 86 is preferably threaded into this dog in position to engage 95 the stem 51 of the left hand auxiliary valve R. The right hand dog is placed in position to engage the wing 75 secured on the stem 51 of the right hand auxiliary valve, when the same is in normal position. But 100 when the wing is swung out of operative position by the movement indicated by dotted lines in Fig. 8, the latch 79 will clear the same.

The mechanism for operating the traverse feed of the grinding wheel will now be described and reference to follow this operation should be had to Figs. 10 and 11. The pipes 66 and 67 extending from the main valve casing are connected to a cylinder 105 87 secured to the front of the frame at the right hand end. A plug 88 with an upwardly extending projection 880 is screwed in the bottom of the cylinder 87. A lower or floating piston 89 provided with an upwardly extending hub 90 is fitted in the cylinder 87. This piston 89 is shown in its lowest position and it will be seen that liquid coming in through the pipe 67 always can act on the bottom of the piston 110 120 125 130

by reason of the projection 880 on the plug 88. An upper piston 91 is also fitted in the cylinder 87 and has a piston rod 92 extending out through a stuffing box 93 secured in the top of the cylinder 87. The upper piston 91 will always be subjected to fluid coming in through the pipe 66 by reason of the hub or upwardly extending projection 90 on the lower or floating piston 89. A spring 94 is arranged around the piston rod and acts to force the upper piston 91 normally to its lowest position. A bracket 95 is secured to the frame or casing A and a limiting screw 96 is threaded therein, this screw being set in position so that the upper end of the piston rod 92 will engage the same. This screw 96 is provided with a knurled head and by turning the same, the upward movement of the piston rod 92 can be adjusted. The screw 96 is provided with a nut 97 so that it can be locked in adjusted position.

When fluid under pressure comes in through the pipe 67, the lower or floating piston will be forced upwardly to strike the upper piston, which then will be forced upwardly until the piston rod 92 engages the end of the adjusting screw 96.

If fluid under pressure comes in through pipes 66, the same will keep the lower or floating piston in its lowest position and will force the upper piston upwardly until the piston rod 92 engages the adjusting screw 96. Thus, if pressure is supplied through either pipe 66 or 67 the piston rod will be lifted or raised until it contacts with the adjusting screw.

By the connections hereinafter described and by the use of this simple mechanism the cross or traverse feed of the grinding wheel can be set to operate at either or both the reversing movements of the work table and the feed movements can be adjusted.

The piston rod 92 is connected to one arm 98 of a three armed lever 98, 99 and 100. The arm 99 of this lever is provided so that the feed can be worked by hand. A pawl 101 is pivoted to the arm 100 of this lever and this pawl engages with a ratchet wheel 102 secured on a quill 103. A hand wheel 104 is also secured on the quill. The quill is journalled on a stud 105 secured in the frame. A pinion 106 is cut on the quill. The three armed lever 98, 99 and 100 turns loosely on the quill and on the hub of the ratchet wheel 102. The pinion 106 engages a gear 107 fastened on the end of a feed screw 108 turning in a bearing 109 secured in the frame A. The feed screw 108 is threaded into a nut 110 secured to the bearing block I. An indicator 111 may be secured to the bracket 95 to register with marks on the ratchet wheel 102 for indicating the amount of feed. The pipes 66 and

67 are provided with valves 112 and 113 so that the feed can take place at either or both reverses of the table movement.

The operation will now be described. Normally the two auxiliary valves are forced outwardly in the casing. This normally will connect the two ends of the main valve to the exhaust. The main valve therefore can be moved to any position by the operating handle W. When the main valve and operating handle are moved to the left as shown in Fig. 12, fluid under pressure is let into the left hand end of the cylinder M and the table is moved to the right, the right hand end of the cylinder being connected to the exhaust. When the operating handle W is moved to the right as indicated in Fig. 13, the right hand end of the cylinder M is connected to the pressure and the left hand end to the exhaust and the table is moved to the left. When the handle is set in the vertical position of Fig. 14 the middle piston 42 of the main valve covers the exhaust passage 55 and the pistons 41 and 42 close the inlet passages 53 and 54 and the movement of the piston N and table B is stopped. Thus, the movements of the table are always within the control of the handle. The speed of the normal movements of the table is regulated by the adjustment of the throttle valve as hereinbefore described. If the handle is pulled outwardly, the throttle valve is opened and the movement takes place at a faster speed.

When a piece of work is to be ground, the same is clamped in the chuck E and the chuck is set in rotation. The grinding wheel is also set in rotation and the same is adjusted to proper transverse position for initial engagement with the inside of the work. The dogs are adjusted in position on the work table so that the table will have the right movement of reciprocation so that the wheel will grind the required distance on the work. The traverse feed of the grinding wheel is adjusted for the right operation at either or both reverses of the work table. These adjustments are preferably made with the work table at its extreme left hand position or as the machine is started in operation. The machine is thrown into operation by throwing the handle to the left as indicated in Fig. 12 so that the table will start on its movement to the right, the latch 79 of the right hand dog snapping over the rocker wing 75. This movement will continue until the left hand dog engages the stem of the left hand auxiliary valve R. This engagement will move the left hand auxiliary valve inwardly and will let the pressure act on the left hand of the main valve. This will shift the main valve to the right as indicated in Fig. 13 and will reverse the movement of the table and start the same on its movement to the right as indicated in Fig. 14. The movement of the table will be stopped when the middle piston 42 of the main valve covers the exhaust passage 55 and the pistons 41 and 42 close the inlet passages 53 and 54 and the movement of the piston N and table B is stopped. Thus, the movements of the table are always within the control of the handle. The speed of the normal movements of the table is regulated by the adjustment of the throttle valve as hereinbefore described. If the handle is pulled outwardly, the throttle valve is opened and the movement takes place at a faster speed.

left. As the table starts on its left hand movement, the left hand auxiliary valve will move to the left back to its normal position. When the table reaches the end of its desired movement to the left, the latch 79 of the right hand dog will engage the wing 75 on the stem of the right hand auxiliary valve and will push the same inwardly which will let pressure on the right hand end of the pilot valve causing the same to shift from the position shown in Fig. 13 back to the position shown in Fig. 12 whereby the movement of the table to the left will be reversed and the same will be started on its movement to the right. Thus, the table will reciprocate backward and forward. As the table reverses at the right hand end of its movement, pressure will be allowed to flow into the pipe 67 and as the table reverses at the left, pressure will be allowed to flow through pipe 66. The pipes 66 and 67 are normally connected to exhaust. Thus the traverse feed of the grinding wheel can take place at either or both reversing movements of the table depending how the valves 112 and 113 are opened.

When it is desired to get a quick movement of the table to its extreme left hand position, as for example for examination or caliperizing of the work or after the piece under operation is ground, the operating handle is pulled way out and is thrown to the right. As the operating handle is pulled way out, by the connections previously described the rocker wing 75 will be moved so that as the table moves rapidly on its movement to the left, the latch 79 will not engage the same. Thus, the table will move quickly to its extreme left hand position. This permits the operator to remove the piece in the chuck that has been ground and to insert a fresh piece. After this is done, the operating handle W can be thrown to the left and the table started on its movement to the right. This can take place at the normal speed as previously described, or if desired, this movement can take place at a high speed until the work engages the grinding wheel by pulling outwardly on the handle W when it is thrown over to the left.

Having thus described my invention and the operation and advantages thereof, it will be evident that changes and modifications can be made therein by those skilled in the art, within the scope of my invention as set forth in the claims and I do not wish to be otherwise limited to the details herein disclosed, but what I claim is:

1. A grinding machine having, in combination, a grinding wheel, a frame, a member fitted to slide thereon to produce relative axial movement of the wheel and work, a cylinder and piston for reciprocating said member, and controlling mechanism therefor normally effective to maintain a given

adjusted uniform rate of travel of said sliding member, said controlling mechanism including a main valve for said cylinder, a speed adjusting device, and a valve which may be actuated to give said member a higher speed when the wheel and work are in spaced relation, while leaving the normal speed adjustment unchanged.

2. A grinding machine having, in combination, a grinding wheel, a frame, a member fitted to slide thereon to produce relative axial movement of the wheel and work, a cylinder and piston for reciprocating said member, controlling mechanism therefor normally effective to maintain a given uniform rate of travel of said sliding member, said controlling mechanism including a main valve for said cylinder and an additional valve which may be actuated to give said member a higher speed to separate the grinding wheel and work or to move them toward each other, and a single manual means controlling said main valve and also said additional valve.

3. A grinding machine having, in combination, a grinding wheel, a frame, a member slidable thereon to produce relative axial movement of the wheel and work, a cylinder and piston to reciprocate said member, and a yielding cushioning connection between said piston and said member.

4. A grinding machine having, in combination, a grinding wheel, a frame, a member fitted to slide thereon to produce relative axial movement of the wheel and work, a cylinder and piston for reciprocating said member, a main valve mechanism controlling said cylinder and piston, means to control the speed of said sliding member, said means including an adjusting device determining the normal speed thereof and a valve movable to give said member a temporary higher speed while leaving the normal speed adjustment of said member unchanged, an auxiliary mechanism controlling said main valve mechanism, and actuating devices for said auxiliary mechanism, whereby the direction of travel may be reversed.

5. A grinding machine having, in combination, a grinding wheel, a frame, a member fitted to slide thereon to produce relative axial movement of the wheel and work, a cylinder and piston for reciprocating said member, and speed-control mechanism for said sliding member, said mechanism including valve mechanism effective to control the movement of said sliding member at a regulated speed, means to adjust said speed, and means effective to cause said sliding member to move at a different speed while said regulated speed adjustment remains unchanged, said regulated valve mechanism being automatically restored to a position of control when said latter means is released.

6. A grinding machine having, in combi-

nation, a grinding wheel, a frame, a member fitted to slide thereon to produce relative axial movement of the wheel and work, a cylinder and piston for reciprocating said member, and speed-control mechanism for said sliding member, said mechanism including valve mechanism effective to control the movement of said sliding member at a regulated speed, means to adjust said speed, means effective to cause said sliding member to move at a different speed while said regulated speed adjustment remains unchanged, and mechanical means to restore said regulated speed when said latter means is released.

7. A grinding machine having, in combination, a grinding wheel, a frame, a member fitted to slide thereon to produce relative axial movement of the wheel and work, a cylinder and piston for reciprocating said member, valve mechanism effective to control the movement of said sliding member at a regulated speed in both directions, means to adjust said regulated speed, and means to increase the speed of movement of said sliding member in both directions while leaving said regulated speed adjustment unchanged, said regulated valve mechanism being automatically restored to a position of control when said latter means is released.

8. A grinding machine having, in combination, a wheel, a frame, a member mounted to slide on said frame to produce relative movement of the wheel and work, a cylinder and piston for reciprocating said member, a valve mechanism controlling the movement of said member at a selected speed, automatic reversing devices for said valve mechanism, additional mechanism controlling the movement of said member at a different speed, and means to disable said automatic reversing devices and to render said latter mechanism operative, said valve mechanism being automatically restored to a condition of control when said additional mechanism becomes inoperative.

9. A grinding machine having, in combination, a wheel, a frame, a member mounted to slide on said frame to produce relative axial movement of the wheel and work, a cylinder and piston for reciprocating said member, a valve mechanism controlling the movement of said member at a selected speed, automatic reversing devices for said valve mechanism, and means additional and separate from said valve mechanism and said reversing devices, effective to cause relative movement of the work and wheel at a different speed, said valve mechanism being automatically restored to a condition of control when said additional means becomes inoperative.

10. A grinding machine having, in combination, a wheel, a frame, a member mount-

ed to slide on said frame to produce relative axial movement of the wheel and work, said member having an operative range of movement with the work in grinding position relatively to the wheel and having an idle position beyond said operative range, a cylinder and piston for reciprocating said member, a valve mechanism controlling the movement of said member when in said operative range and fixing the rate of movement within said range at a predetermined selected speed, reversing devices for said valve mechanism, and means additional and separate from said valve mechanism and said reversing devices effective to cause relative movement of the work and wheel toward and thereafter away from idle position when said member is out of said operative range and at a higher rate of travel.

11. A grinding machine having, in combination, a wheel, a frame, a member mounted to slide on said frame to produce relative axial movement of the wheel and work, means to reciprocate said member at a selected speed, automatic reversing devices for said reciprocating means, and means to render one of said reversing devices inoperative and to thereafter move said member axially at an increased speed.

12. A grinding machine having, in combination, a frame, a member mounted to slide on said frame to produce relative axial movement of the wheel and work, means to reciprocate said member at a selected speed, automatic reversing devices for said reciprocating means, and a single manually operated reversing device effective to independently determine the direction of travel of said member and also to increase the rate of travel of said member.

13. A grinding machine having, in combination, a wheel, a frame, a table slidable on said frame, a cylinder and piston effective to move said table longitudinally relatively to the axis of said wheel, a cross feed effective to move said wheel transversely to said table, a cylinder and piston connected to actuate said cross feed, and controlling connections from said first cylinder to said second cylinder whereby said cross feed will be actuated upon reversal of movement of said table at one end of the table travel.

14. A grinding machine having, in combination, a wheel, a frame, a table slidable on said frame, a cylinder and piston effective to move said table longitudinally relatively to the axis of said wheel, a cross feed effective to move said wheel transversely to said table, a cylinder and piston connected to actuate said cross feed, controlling connections from said first cylinder to said second cylinder whereby said cross feed will be actuated upon reversal of table movement, and manually operable valves in said connec-

- tions effective to selectively render said cross feed operative at either or both ends of the table travel.
15. A grinding machine having, in combination, a wheel, a frame, a member slideable thereon to produce relative axial movement of the wheel and work, fluid operated actuating devices for said member, valve mechanism for said devices, automatic controlling and reversing devices for said valve mechanism, and a single lever effective to disable said automatic controlling and reversing devices and to manually control the direction and rate of movement of said member, said automatic controlling and reversing devices automatically resuming control of the travel of said member whenever said single lever is released and becomes inoperative.
20. 16. A grinding machine having, in combination, a wheel, a frame, a member slideable thereon, a cylinder and piston connected to reciprocate said member to produce relative longitudinal movement of the work and wheel, a main valve mechanism for said cylinder and piston, and an auxiliary valve mechanism for controlling said main valve mechanism, said auxiliary valve mechanism being automatically controlled by engagement with portions of said moving member.
25. 17. A grinding machine having, in combination, a wheel, a frame, a member slideable thereon to produce relative axial movement of the wheel and work, a cylinder and piston connected to reciprocate said member, a main valve mechanism for said cylinder and piston, an auxiliary mechanism for controlling said main valve mechanism, said auxiliary mechanism being automatically controlled by engagement with portions of said moving member, and an additional manually operable handle effective to independently control said main valve mechanism.
30. 18. A grinding machine having, in combination, a wheel, a frame, a member slideable thereon, a cylinder and piston connected to reciprocate said member to produce relative longitudinal movement of the work and wheel, a main valve mechanism for said cylinder and piston, an auxiliary mechanism for controlling said main valve mechanism, said auxiliary mechanism being automatically controlled by engagement with portions of said moving member, and an additional manually operable handle effective to independently control said main valve mechanism.
35. 19. A grinding machine having, in combination, a wheel, a frame, a member slideable thereon, a cylinder and piston connect-
- ed to reciprocate said member to produce relative longitudinal movement of the work and wheel, a main valve mechanism for said cylinder and piston, an auxiliary mechanism for controlling said main valve mechanism, said auxiliary mechanism being automatically controlled by engagement with portions of said member, a throttle valve to control the flow of fluid to said main valve mechanism, and a single manually operable handle connected to control both the main valve mechanism and said throttle valve.
40. 20. An internal grinding machine having, in combination, a wheel, a frame, a member mounted to slide on said frame to produce relative axial movement of the wheel and work, a cylinder and piston for reciprocating said member, a valve mechanism for said cylinder and piston, stops on said member adjustable longitudinally thereof, control means engaged by said stops to control said valve mechanism, thereby normally limiting the travel of said member in both directions, and additional means effective to produce relative movement of said control means and one of said stops to prevent operative engagement thereof while maintaining the adjusted position of said stop.
45. 21. An internal grinding machine having, in combination, a wheel, a frame, a member mounted to slide on said frame to produce relative axial movement of the wheel and work, a cylinder and piston for reciprocating said member, a valve mechanism for said cylinder and piston, stops on said member adjustable longitudinally thereof, control means engaged by said stops to control said valve mechanism, thereby normally limiting the travel of said member in both directions, and additional manual means effective to produce relative movement of said control means and one of said stops to prevent operative engagement thereof, while maintaining the adjusted position of said stop, thereby permitting said parts to pass without reversing the travel of said member, one of said parts yielding upon the return movement of said member to restore normal operative relations of said device and stops.
50. 22. An internal grinding machine having, in combination, a wheel, a frame, a member mounted to slide on said frame to produce relative axial movement of the wheel and work, a cylinder and piston for reciprocating said member, a piston valve having a plurality of pistons thereon effective to control the passage of pressure fluid toward and from said piston and cylinder, and a manually operable device effective to move said piston valve to a neutral position and stop said member at any point in the stroke of said piston, said piston valve having the opposed pressures thereon equalized

during substantially the entire travel of said member and thereby permitting free movement of said piston valve by said manually operable device.

5 23. An internal grinding machine having, in combination a wheel, a frame, a member mounted to slide on said frame to produce relative axial movement of the wheel and work, a cylinder and piston for reciprocating said member, a valve mechanism for said cylinder and piston, auxiliary mechanism controlling said valve mechanism, a cross feed mechanism for effecting relative transverse movement of the work and wheel, 10 said mechanism including a cylinder and piston, and a connection from said first named cylinder to said cross feed cylinder, said connection being opened by said auxiliary mechanism to periodically admit pressure to said latter cylinder to actuate said cross feed.

24. In a grinding machine, the combination of a frame, a moving member fitted to slide thereon, a cylinder and piston for reciprocating said member, a main valve for controlling the flow of actuating fluid under pressure to said cylinder, a feeding device, a second cylinder and piston connected to actuate said feeding device, and connections 30 for transferring fluid under pressure between said main valve and said second cylinder, said fluid being effective to cause movement of said second piston to actuate said feeding device upon movement of said 35 main valve to one of its two operative positions.

25. In a grinding machine, the combination of a frame, a moving member fitted to slide thereon, a cylinder and piston for reciprocating the member, a main valve for controlling the flow to the cylinder, auxiliary valve mechanism connected to control the movements of the main valve, dogs on the moving member for operating the auxiliary 40 valve mechanism, a feeding device, a second cylinder having a piston therein connected to operate said feeding device, and connections for transferring fluid under pressure 45

between the valve mechanism for the first cylinder and said second cylinder, said fluid being effective to actuate said second piston and operate said feeding device when the valve mechanism for the first cylinder is actuated.

26. In a grinding machine, the combination of a frame, a moving member fitted to slide thereon, a cylinder and piston for reciprocating the member, a main valve for controlling the flow to the cylinder, two auxiliary valves connected to control the movements of the main valve, dogs on the moving member for operating the auxiliary valves, a feeding device, a second cylinder having an actuating piston therein connected to move said feeding device, a floating piston therein adapted to engage said actuating piston, and connections between said main valve and said second cylinder effective to admit actuating fluid under pressure behind one or both of said pistons in said second cylinder when pressure is admitted to move said main valve to either of its operative positions, thereby actuating said feeding device at both reversals of movement of said moving member.

27. In a grinding machine, a fluid pressure operated feed mechanism having in combination a frame, a moving member fitted to slide thereon, a cylinder and piston for reciprocating said member, automatic reversing devices for said reciprocating means, a second moving member, a second cylinder having a piston connected to move said second member, and connections for fluid under pressure between said reversing devices and said second cylinder through which connections said second piston is caused to move intermittently in the same direction at each reversal of travel of said first moving member, said second piston thereby causing movement of said second moving member in predetermined relation to the movement of said first member.

In testimony whereof I have hereunto affixed my signature.

RALPH L. MORGAN.
